UNITED STATES PATENT OFFICE.

FRIEDRICH HÜRZELER, OF ST. GALL, SWITZERLAND.

FABRIC-HOLDING FRAME FOR EMBROIDERING-MACHINES.

SPECIFICATION forming part of Letters Patent No. 478,192, dated July 5, 1892.

Application filed February 1, 1892. Serial No. 419,868. (No model.)

To all whom it may concern:

Be it known that I, FRIEDRICH HÜRZELER, a citizen of Switzerland, residing at St. Gall, in the canton of St. Gall and Republic of Switzerland, have invented certain new and useful Improvements in Round Removable Fabric-Holding Frames for Embroidering-Machines; and I do hereby declare the following to be a full, clear, and exact description of the invention, such as will enable others skilled in the art to which it appertains to make and use the same.

The object of this invention is an improvement in round removable fabric-holding frames for placing or hanging in the frame of ordinary embroidery-machines.

Figure 1 of the annexed drawings shows a portion of a frame with two removable round embroidery-frames; Fig. 2, the same with four and a fragment of a fifth embroidery-frame, and Fig. 3 a section along the line X of Fig. 2.

A shows the frame of the embroidery-machine, on which the supporting-plate *a* is fastened in a suitable manner. These small plates *a* are each provided with a pin *b*, on which the embroidery-frames *C* are hung, and are provided with holes *c c'* at even distances from one another. For instance, in *c c'* the holes

are for division of the surface of the embroidery into sixths, and *c' c'* are for division into eighths. It should be understood that the stretching-frame can also be provided with the suspending-holes required for any other divisions and that the holes can have any suitable form, as shown in Fig. 2. The suspension of the frames *C*, also, can be obtained by means of the notches *i*, arranged on the inner edge of the frames *C*, or by means of radial grooves

i', cut in one side of the frames, which notches or grooves are put on corresponding pins or bosses *b*, on which the frames are hung. When one section of the surface has been embroidered, the frame is turned to a further section, so that an unembroidered surface is in front of the needle. In this way large and small designs—such as stars, bouquets,

wreaths, &c.—can be embroidered, and, when necessary, by means of the ordinary festooning apparatus edging and festooning can be 50 accomplished on the round stretching-frames. By a suitable clamp *D* the round embroidery-frame is held in the position in which it is placed.

In order that borders and edgings may be 55 embroidered in as many frames as possible simultaneously, a third embroidery-frame is laid on each two adjacent frames, so that the surfaces of the fabric lie close together, one over another, Fig. 2. The plates *a'*, which 60 serve to support the second series of frames, are higher than the plates *a* by the thickness of a frame, Fig. 3. To allow of the embroidery of the portions in the centers of the frames, the second series of frames are removed. The stretching of the fabric is 65 accomplished either by means of the stretching-ring *d*, which presses the fabric into a groove on the circumference of the frame, or by means of spikes *e*, set in the edge of the frame, over 70 which the fabric is drawn. The former is chiefly adapted for use in embroidering large bouquets, stars, rosettes, &c., in the middle of large cloths, pillow-cases, table-cloths, shawls, &c.; the latter for use in embroidering 75 small cloths for tables, arm-chairs, arm-sofa cushions, mats for vases, lamps, table-linen, caps, &c.

On both systems of frames designs in great numbers can be embroidered. 80

I claim—

In combination with the frame proper of an embroidery-machine, a round removable fabric-holding frame provided with a series of holes placed at equal distances around its 85 periphery, pins mounted on said frame proper to engage said holes, and clamps to preserve said engagement, substantially as set forth.

In testimony whereof I affix my signature in presence of two witnesses.

FRIEDRICH HÜRZELER.
